Primary Examiner — Steven J Czyz(74) *Attorney, Agent, or Firm* — Laubscher & Laubscher, P.C.(57) **CLAIM**

The ornamental design for a floor stand, as shown and described.

DESCRIPTION

FIG. 1 is a front perspective view of a floor stand according to my invention;

FIG. 2 is a right side elevation view thereof;

FIG. 3 is a front elevation view thereof;

FIG. 4 is a left side elevation view thereof;

FIG. 5 is a rear elevation view thereof;

FIG. 6 is a top plan view thereof; and,

FIG. 7 is a bottom plan view thereof.

The broken lines in the drawing represent portions of the article which form no part of the claimed design.
